CLAIM

The ornamental design for a display screen with animated graphical user interface, as shown and described.

DESCRIPTION

FIG. 1 is a front view of a first image of a display screen with animated graphical user interface showing our new design;

FIG. 2 is a front view of a second image thereof;

FIG. 3 is a front view of a third image thereof;

FIG. 4 is a front view of a fourth image thereof; and,

FIG. 5 is a front view of a fifth image thereof.

The broken lines of uneven length show the display screen and form no part of the claimed design. The broken lines of even length show in the drawing illustrates portions of the display screen with user interface that form no part of the claimed design.

1 Claim, 5 Drawing Sheets
